UNITED STATES PATENT OFFICE.

HENRY CHESS AND HARVEY B. CHESS, OF PITTSBURG, PENNSYLVANIA.

ROLL-BRASSES AND METHOD OF MAKING THE SAME.

SPECIFICATION forming part of Letters Patent No. 290,535, dated December 18, 1883.

Application filed November 1, 1883. (No model.)

To all whom it may concern:

Be it known that we, HENRY CHESS and HARVEY B. CHESS, of Pittsburg, Pennsylvania, have invented a new and useful Improvement 5 in Roll-Brasses and Method of Making the Same, of which the following is a full, clear, and exact description, reference being had to the accompanying drawings, making a part of this specification, in which—

10 Figure 1 is a transverse section of a pair of rolls, showing our improved brasses applied. Fig. 2 is a longitudinal section through one of the brasses. Fig. 3 shows the method of fitting the brasses. Fig. 4 shows a modification. Fig. 5 shows details to be referred to.

15 Our present invention refers to roll-brasses and the method of constructing the same; and it consists in a novel form in which the brasses are constructed, so as to admit of easy change 20 or substitution, and fitting the same entirely by lathe-work, and also a method of assisting in the retention of the lubricating material, which, between the heat and excessive pressure to which roll-bearings are subjected, is not 25 easily retained in position.

25 In the manufacture of these brasses we prefer to make the two brasses A A, or a pair of brasses, at one casting, as shown in Fig. 3, so as to form continuous parts of a cylinder. 30 These parts A A are attached to each other by slight bridges or stays, a a, in the casting. The flange is then chuck'd into a lathe, the inside bored out to standard measure, and the outside turned off also to standard measure. The 35 bridges are then broken out and the two brasses are complete. Three or more brasses may be cast in this manner and finished at the same time. To retain these shells or brasses in position in the blocks and to prevent them from 40 revolving out of place we cast lugs b b on the flanges, which fit into corresponding recesses made in the pillow-blocks C, or in the carriages or riders. There is no conjunction of this lug with the cylindrical part of the brasses; as 45 shown at the chamfers c c in Fig. 2. This absence of any conjunction with the cylindrical part of the brasses permits the advance of the lathe-tool entirely up to the flange. It is evident that by this uniformity of the section 50 throughout each portion of the brasses is

equally strong, and this greatly lessens the danger of damage from breaking at any weak point, as is the case with brasses as now made with a flattened base, as shown at D, Fig. 5. It is also evident that, should the brasses become excessively heated, as is the case sometimes in quick and high-speed trains, our improved form permits an easy expansion in its bearings from its center or lug outward and around in each direction, which is an essential 60 feature of our invention. Again, where limited space is had between the necks, this new form permits a strong construction in the form of the pillow-blocks, carriages, and riders by avoidance of the square recesses and short angles and abrupt change of sections necessitated by the use of brasses with square bases. Again, 65 we effect a great economy of costly material. Single brasses may be made with thickened bottoms by eccentric boring, as shown in Fig. 70 4, which will fit in the same bored recess.

It is a well-known fact that excessive waste of lubricating material used in roll-brasses goes on by leakage and by non-retention on the side of the brasses toward the coupling. Another 75 essential object of our invention is to retard or check this leakage or waste. It is also well known that oil or other viscid material will not, on journals, travel over a groove or pass through a smaller diameter if the motion 80 of the journal be rapid, owing to the centrifugal force exerted on it. If the motion be slow, the trough-like action of the raised edge d, as shown in Fig. 2, will retain the lubricating material; hence in turning the roll-neck we sink 85 the neck at the end next to the coupling for the space of about half an inch, or to a diameter equal to that of the coupling, the latter being invariably from one-half to an inch smaller 90 in diameter. The flange d, projecting inward, is left on the brasses at the side next to the coupling, as before stated, which flange is made by boring the brasses to match the turned depression at the end of the neck, as shown in Fig. 2. This system is peculiarly applicable 95 when bearings are made of Babbitt or other like metals poured with the roll in place.

Having thus described our invention, what we claim as new, and desire to secure by Letters Patent, is—

1. As a new article of manufacture, roll-brasses A, of uniform thickness throughout, and provided with the lugs b and flange d, substantially as and for the purpose set forth.
- 5 2. The method herein described of making roll-brasses, the same consisting of casting two or more brasses so as to form continuous parts of a cylinder, the parts being connected by

bridges or stays in castings, whereby they are capable of being finished and fitted by lathe-work, substantially as described.

HENRY CHESS.
HARVEY B. CHESS.
